UNITED STATES PATENT OFFICE

2,351,064

ENGINE FUEL PUMP

Lewis Pengilly, Loma Mar, Calif.

Application September 8, 1941, Serial No. 409,942

8 Claims. (Cl. 103—164)

This invention relates particularly to a fuel pump for an internal combustion engine wherein the fuel is raised from a fuel tank, placed at a lower level, to the level of the engine carburetor.

An object of the invention is to provide a pump of simple construction, together with piping and check valves, for supplying fuel to an engine carburetor which will automatically cease supplying fuel when the carburetor is full, and automatically replenish the supply when the level of gasoline in the carburetor falls.

A further object of the invention is to provide an apparatus for raising a liquid from one level to another which includes a pump for setting a column of liquid in pulsating motion by unidirectional impulses in combination with valves operating in timed relation, to prevent return to the source of supply of the entire amount of liquid advanced and yet to accomplish the discharge of a part of the liquid advanced.

These and other objects will appear as the description of the invention advances.

In the drawing:

Fig. 1 is a schematic lay-out of an automobile engine and fuel tank having a pumping mechanism and piping, constructed in accordance with my invention (diagrammatically illustrated) applied thereto.

Fig. 2 is a vertical section through the fuel pump to the interior construction thereof.

Fig. 3 is a vertical section through the fuel tank, valve chamber assembly.

In detail the construction illustrated in the drawing consists of an internal combustion engine generally designated by the numeral 1, and a fuel tank indicated by 2. The engine 1 has a carburetor 3 thereon provided with the usual fuel bowl and float valve within the bowl.

The carburetor 3 is connected by a fuel pipe 4 to a valve chamber assembly 5 located within the fuel tank 2 near the bottom thereof to be submerged by the fuel.

On the engine 1 I have located a pump 6. The pump 6 is directly connected to and operates in unison with the engine. The pump 6 is connected by an air line 7 to the valve chamber assembly 5 in the tank 2.

The pump 6 consists of a cylinder 8 having a piston 9 therein. The piston 9 is provided with an annular groove 10 at a selected point between the top and bottom thereof and a hole 11 is provided in the wall of the piston, between the top thereof and groove 10.

The cylinder 8 is provided with two, spaced ports 12 and 13, the upper port 12 being an air

inlet and the lower port 13 being a pressure outlet to the valve chamber assembly in the fuel tank. A passage 14 is provided in the cylinder wall to connect the ports 12 and 13, which ports are located in a selected position in relation to the groove 10 in the piston to effect the working of the assembly as will be more fully disclosed hereinafter. The inlet or suction port 12 is provided with a check valve 15 to allow sufficient air to enter the cylinder in order that a maximum air pressure may be maintained when the pump is in operation.

The valve chamber 5 is provided with separated check valves 16 and 17 therein, the valve 16 being in the bottom of the chamber 5 and the valve 17 being in the fuel line and above the valve 16.

The assembly operates to pump fuel from the tank 2 to the carburetor 3 as follows:

Upon operation of the engine 1, the pump 6 is put in motion. On the down stroke of the piston 9, a suction is created in the cylinder head, which reacts through the air line 7 to lift the bottom check valve 16 and suck fuel through the screen strainer 18 into the chamber 5; but the force of this suction is limited by the spring-seated check valve 15 which will open occasionally to replenish air in the line 7 to the extent that such air is mixed with the fuel in chamber 5 and passed along to the carburetor therewith.

On the up stroke of the piston a pressure is created which causes the air inlet valve 15 to close and accumulated air pressure above the piston 9 to pass downwardly through the hole 11, to the piston groove 10 through which it passes to the outlet port 13 and thence through the air line 7 to the valve chamber 5. The pressure in the valve chamber 5 forces the fuel contained therein upwardly and outwardly through the check valve 17, and fuel line 4 to the fuel bowl of the carburetor 3.

On the following strokes of the piston the action above described is repeated.

The check valve 16 is calibrated so that when the pump is not in operation, the valve chamber 5 and the end of the fuel line 4 within the fuel tank will automatically fill with fuel to a height equal to the level of the fuel in the tank. However where the fuel is being consumed rapidly, it is necessary to utilize the intermittent suction effect described to maintain the proper amount of fuel within the valve chamber 5.

The pump 6 is so constructed that the suction stroke of the piston creates only a small amount of suction capable of drawing fuel through the inlet valve 16 into the chamber 5, and up into

the air line 7 to a height slightly above the level of the fuel in the tank. No matter how many times the piston reciprocates, it will not suck the fuel above said level, therefore the fuel at no time can be drawn up into the pump. An inverted siphon is formed in the air line 7 by extending the pipe 7 a distance above the fuel level in excess of that through which the suction or "vacuum" effect could be operative.

The pressure stroke of the piston provides enough pressure to force the fuel from the valve chamber 5 to the carburetor and yet maintains a constant pressure sufficient for the proper operation of the carburetor. However the pump will not create a pressure in the valve chamber 5, greater than is necessary to supply fuel to the carburetor properly regardless of the number of times the pump operates and regardless of how fast or how slow the fuel may be released through the carburetor.

While I have shown the inlet port 13 located in the cylinder wall so as to register with the piston groove 10 when the piston is at the top of the stroke, the same effect could be accomplished by providing the inlet through the cylinder wall to communicate with the piston groove 10 when the piston is at the bottom of its stroke.

Having thus described this invention, what I claim and desire to secure by Letters Patent is:

1. In a liquid elevating system which includes a chamber having an outwardly seating inlet valve and an inwardly seating outlet valve, a delivery pipe controlled by the latter valve and an air pipe leading to said chamber, a pump comprising a cylinder, a piston reciprocable therein, said cylinder having a port opening into said air pipe, means for releasing a pressure impulse through said port substantially at the end of the compression stroke of the piston and applying a suction impulse to said air pipe upon the return stroke, and means automatically limiting the degree of vacuum created in the air pipe by said suction impulse.

2. In a liquid elevating system which includes a chamber having an outwardly seating inlet valve and an inwardly seating outlet valve, a delivery pipe controlled by the latter valve and an air pipe leading to said chamber, a pump comprising a cylinder, a piston reciprocable therein creating alternate pressure and suction impulses, said cylinder having a port opening into said air pipe, means for releasing the pressure impulses to said chamber through said port and means limiting the corresponding suction impulses acting through said port to produce a series of impulses effective principally in one direction for elevating liquid from said chamber.

3. In a liquid elevating system which includes a chamber having an outwardly seating inlet valve and an inwardly seating outlet valve, a delivery pipe controlled by the latter valve and an air pipe leading to said chamber, a pump comprising a cylinder, and a piston reciprocable therein, said pump having a pressure outlet port opened by the piston substantially at the end of its compression stroke and a suction port opened by the piston during its return stroke, said suction port communicating simultaneously with the air pipe leading to said chamber and with an air inlet admitting atmospheric pressure and thus limiting the suction and replenishing air expelled from the air pipe by the compression stroke.

4. In the combination defined in claim 3, an automatically seating check valve in the atmosphere inlet preventing the release of air through said inlet during the compression stroke.

5. In a liquid elevating system which includes a chamber having an outwardly seating inlet valve and an inwardly seating outlet valve, a delivery pipe controlled by the latter valve and an air pipe leading to said chamber, a pump comprising a cylinder, a piston reciprocable therein, said cylinder having a port opening into said air pipe, means for releasing pressure impulses from the pump through said port to said chamber, and means limiting the corresponding suction impulses to produce a series of impulses effective principally in one direction for elevating liquid from said chamber, said pump being mounted above the level of liquid in the chamber and a portion of said air pipe extending above the chamber to a level higher than that to which the limited suction is capable of elevating the liquid.

6. In a liquid elevating system, a continuously operable pump including a cylinder with a piston reciprocable therein, a liquid fuel supply tank disposed at a level normally below the point at which the liquid is delivered and below the level of the pump, a chamber submerged in said tank having an outwardly seating inlet valve and an inwardly seating outlet valve, a delivery pipe controlled by the outlet valve and leading to the point of delivery, an air pipe connecting said chamber with the pump cylinder, the connection being by way of a port in the cylinder, means for releasing a pressure impulse through said port substantially at the end of the compression stroke of the piston, and means automatically admitting atmospheric air to the cylinder during each return stroke of the piston except when the flow of liquid is resisted at the point of delivery, causing the cylinder pressure to remain above a predetermined limit throughout the pump cycle.

7. In a liquid elevating system, a continuously operable pump including a cylinder with a piston reciprocable therein, a liquid fuel supply tank disposed at a level normally below the point at which the liquid is delivered and below the level of the pump, a chamber submerged in said tank having an outwardly seating inlet valve and an inwardly seating outlet valve, a delivery pipe controlled by the outlet valve and leading upwardly and directly to the point of delivery, an air pipe connecting said chamber with the pump cylinder, the connection being by way of a port in the cylinder, means for releasing a pressure impulse through said port to said chamber substantially at the end of the compression stroke of the piston, and means limiting the corresponding suction impulse applied to said air pipe upon the return stroke whereby the pressure impulses operate to advance liquid from the chamber toward the point of delivery and the limited suction impulses insure opening of the inlet valve of said chamber.

8. In the combination defined in claim 3, a spring-seated check valve in the atmosphere inlet preventing release of air through said inlet during the compression stroke and including means adjustable to vary the spring tension by which the check valve is held seated.

LEWIS PENGILLY.
